UNITED STATES PATENT OFFICE.

CHARLES E. JEWELL, OF SENECA FALLS, NEW YORK.

ADJUSTABLE HANGER OR SUPPORT.

Application filed March 13, 1926. Serial No. 34,623.

The object of this invention is to provide a new and improved form of spring supporting devices for various objects more especially small objects.

5 This and other objects of the invention will be fully illustrated in the drawing, described in the specification and pointed out in the claims at the end thereof.

In the drawings:

10 Figure 1 shows a spring support for an incandescent lamp when used as a floor lamp.

Figure 2 shows a modification of the same invention fastened to a picture frame for the purpose of supporting it from a molding, etc.

15 Figure 3 is another modification of the spring support applied to a picture frame for the purpose of supporting it from a molding.

20 In the drawings like reference numerals indicate like parts.

In the drawings reference numeral 1 indicates a spring sheet metal support of my invention which is adapted to engage with a

25 round rod and hold itself in place thereon, or hold the rod supported thereby. For this purpose the spring support comprises two members A and B joined together at the base C and formed so as to be suitably spaced apart at the outer ends. At the

30 outer ends they are suitably perforated so as to receive the rod 2 in this case, which is attached to a pedestal 3 by which the rod is held in an upright position from the floor.

35 The rod 2 may be round which will permit the support to swing sideways or may be square or oval with perforations in the support to correspond in which case the support will be held against swinging. To this

40 support is attached a suitable yoke that engages with the socket of an incandescent lamp so that the lamp is supported thereby. This yoke is made in one piece and the two sides of it are held together so as to closely

45 embrace the lamp by the clips 4 and 5 which are of the shape of a fork and slid down over the two side members of the yoke so as to hold them closely together. The base of the yoke is fastened to the base of the support

50 by a small bolt and nut. By pressing the outer ends of the two members A and B of the support together it is released from the upright so that it can be moved along the

55 upright and when the members A and B are released they spring apart and engage the upright so as to hold themselves securely

thereon. The holes in the supporting members A and B are slightly larger than the rod with which they engage, so as to slide freely thereon when standing at right angles thereto, that is when gripped together, but so as to grip the rod when they are spread apart and slightly inclined thereto. The more they are spread the tighter they will grip.

5 In Figure 2 I have shown the spring members 7 and 8 fastened together by a bolt 9 and attached to an angle bracket 10. At the outer ends, the spring members are bent apart and are suitably perforated to receive the rods 11 and 12 with which they engage 60 and lock. The angle bracket 10 is attached to a picture frame for example, and by this device the picture frame is supported. The upper ends of the rods 11 and 12 are joined together and bent over in the form of a hook 70 that will engage a picture molding or any other suitable support. By bringing the loose ends of the springs 7 and 8 together the rods 11 and 12 are released and may be moved up or down as may be desired and the 75 picture may be hung to correspond. This permits the adjustment to be made before the picture is hung.

80 In Figure 3 I have shown another type of support in which the spring members are joined together by the base 15. To this base is attached the bracket 16 which is bent in the opposite direction from the spring members and is parallel to the sides of them. This bracket can also be attached to a picture frame and the spring members can engage a supporting rod 17, the upper end 18 of this rod is hook shaped and is adapted to engage a molding or any other suitable support. I have shown the bracket 16 attached 90 to the picture frame with two screws. This prevents it from swinging. One screw only may be used which will permit it to swing and this will rather increase its gripping effect on the rod 17.

95 Spring supporting devices made in this way adapt themselves to a great variety of uses aside from those shown. Two of the devices shown in Figures 1 and 2 can be adapted to support a shelf, one of them can be used to support a mirror. The devices of Figures 2 and 3 can be used to support a sash, etc. and so on indefinitely.

100 I claim:

1. A spring supporting device comprising 110 two plates formed of spring metal normally standing apart at both ends and joined to-

gether between the ends, each plate having a hole therein at each end, a pair of rods held fixed with relation to each other passing through the holes of both plates at each end thereof, the plates being adapted to slide on the rods when pressed together and being adapted to grip the rods when sprung apart.

2. A spring supporting device comprising two plates formed of spring metal normally standing apart at both ends and joined together between the ends, each plate having a hole therein at each end, rods passing through the holes of both plates at each end thereof said rods being joined together at one end, the plates being adapted to slide on the rods when pressed together and being adapted to grip the rods when sprung apart, a bracket attached to said plates by which it

may be attached to some object by which it is supported or which is to be supported thereby.

3. A spring supporting device comprising a pair of bow shaped plates fastened together back to back in the middle thereof, each end of said bow shaped plates having a hole therein, the holes of one bow shaped plate being normally slightly out of line with the holes of the other bow shaped plate, a pair of rods passing thru the opposing pair of holes of said bow shaped plates, a hook formed at one end of each of said pair of rods, and a link connecting the free ends of said hooks.

In testimony whereof I affix my signature.

CHARLES E. JEWELL.
